UNITED STATES PATENT OFFICE.

OSCAR BENDER, OF POTSDAM, GERMANY.

PROCESS FOR PRODUCING NITROGEN COMPOUNDS.

1,172,863.

Specification of Letters Patent. Patented Feb. 22, 1916.

No Drawing.

Application filed July 2, 1914. Serial No. 848,575.

To all whom it may concern:

Be it known that I, OSCAR BENDER, a subject of the German Emperor, residing at Potsdam, Germany, have invented a new and useful Process for Producing Nitrogen Compounds, of which the following is a specification:

My invention relates to improvements in the process for producing nitrogen-oxygen and nitrogen-hydrogen compounds, and more particularly in the process in which the said compounds are produced by combustion of a suitable fuel by means of air under a pressure which is above atmospheric pressure, and which is say 1, 2, 3, 4, and more atmospheres.

As is known in the art the rapidity and completeness of chemical reactions are considerably increased in the presence of elements in *statu nascendi*. If a suitable amount of water in a state of fine distribution or atomization is added to the air for supporting combustion of a fuel or to the fuel, the said water is split more or less into its elements. The air contains about 21 per cent. of oxygen the whole amount of which can be found in the combustion gases in the form of carbonic acid, carbonous oxid, and a residue of free oxygen. When adding a suitable amount of water in a state of fine distribution to the air for supporting combustion or to the fuel of a generator, and carrying out the combustion under pressure the air or the fuel can take up an increased amount of finely divided water by reason of their increased compression. I have found that under such circumstances a large amount of finely divided water can be taken up. For example under a pressure of one atmosphere above atmospheric pressure per one kilogram of coal 0.800 kilogram of water can be taken up, in which case the gases of combustion do not contain as an aggregate only 21 per cent. of oxygen in the form of carbonic acid, carbonous oxid, and free oxygen, but the amount is considerably increased, the amount of oxygen being in some cases as high as 26 per cent., so that there is say 13 per cent. of carbonic acid and 13 per cent. of oxygen in the gases of combustion. It follows from this, that apart from the oxygen of the air which can not supply more than 21 per cent., a further amount of oxygen has been supplied by splitting the water.

55 In the example referred to, in which 26

per cent. of oxygen is found in the gases of combustion, 5 per cent. of oxygen is taken from the water. Therefore according to the symbol H_2O of the water 10 per cent. of hydrogen must have entered into the reaction in a different form.

The analysis of the gases of combustion shows that apart from a considerable amount of NO further amounts of nitrogen-hydrogen compounds have been formed. Therefore, a large amount of the water has been split, the elements thereof having entered into the reaction in *statu nascendi* and having formed corresponding amounts of nitrogen-hydrogen compounds apart from the NO.

The formation of the nitrogen compounds is most active at those parts of the reaction chamber where there are the highest temperatures. Therefore, at these parts care must be taken that the nitrogen compounds which are at equilibrium at the highest temperatures, are fixed or frozen by suddenly cooling the same. For example, in a generator for solid fuel the highest temperatures prevail within that zone of the fuel and more particularly at such places where the carbon combines with the oxygen, and therefore, at these places cooling must be most intensive and sudden. Preferably cooling is effected by means of hollow metallic bodies of large surface area which are cooled by means of a suitable cooling medium such as water, air, or the like which is circulated therethrough.

I prefer to use a system of grates which is cooled by water. The combustion is carried out in such a way, that the most vehement oxidation of the carbon takes place on the surface of the grating being cooled, while the ashes and other residues fall through the grating by the sudden cooling. Simultaneously the nitrogen and the oxygen and hydrogen are brought into a state of equilibrium, and the gases or compounds are suddenly cooled and fixed. Thereby large amounts of nitrogen are formed; one kilogram of carbon being able to produce about 100 grams of nitrogen compounds.

By carrying out the reaction above atmospheric pressure the combustion is accelerated according to the height of the pressure, so that a higher temperature is obtained and a greater amount of nitrogen compounds is formed. Therefore, I prefer

to carry out the process under a pressure which is above atmospheric pressure, say 1, 2, 3, 4, 5, or more atmospheres.

I have found that with a temperature of about 2000 degrees centigrade within the furnace about one per cent. by volume of NO, and about one quarter of a per cent. by volume of NH₃, are formed, which are in mixture with CO₂N and free oxygen and leave the furnace in the form of a white fog. After a short time ammonium nitrite NH₄NO₂ with an excess of HNO₂ or HNO₃ at the above ratio can be proved.

It will be obvious that in carrying out my process it will be necessary to regulate the amount of air, water and fuel so that the highest yield in oxid may be obtained.

To increase the output in nitrogen-hydrogen and nitrogen-oxygen compounds a suitable amount of nitrogen carriers may be added to the water, to the fuel, or to the air for supporting combustion. These nitrogen carriers may be substances or compounds which are chemically in equilibrium with nitrogen at comparatively low temperatures. Such substances are particularly aluminium oxid (Al₂O₃) or the compounds thereof, calcium or the like. In my improved process the said nitrogen carriers, such as aluminium oxid or compounds thereof, which are more or less soluble in water are admixed to the water to be entered into the reaction, whereupon the water is split in the manner indicated, and the aluminium oxid which has been added to the water is simultaneously highly superheated, and they are easily brought into chemical equilibrium with the superheated nitrogen which is already present in the reaction and enter into reaction therewith. Also when adding nitrogen carriers the process is carried out in the manner described.

I claim herein as my invention:

1. The herein described process of obtaining nitrogen compounds, which consists in burning a suitable fuel by means of air and in the presence of water and a nitrogen carrier, and separating the nitrogen compounds from the products of combustion.

2. The herein described process of obtaining nitrogen compounds, which consists in burning a suitable fuel by means of air and in the presence of water and aluminium oxid, and separating the nitrogen compounds from the products of combustion.

3. The herein described process of obtaining nitrogen compounds, which consists in

burning a suitable fuel by means of air and in the presence of water and a compound containing aluminium and oxygen, and separating the nitrogen compounds from the products of combustion.

4. The herein described process of obtaining nitrogen compounds, which consists in burning a suitable fuel by means of air and in the presence of water and a nitrogen carrier and under pressure, and separating the nitrogen compounds from the products of combustion.

5. The herein described process of obtaining nitrogen compounds, which consists in burning a suitable fuel by means of air and in the presence of water and aluminium oxid, and cooling the combustion gases in the zone of highest temperature, and separating the nitrogen compounds from the products of combustion.

6. The herein described process of obtaining nitrogen compounds, which consists in burning a suitable fuel by means of air and in the presence of water and a nitrogen carrier, and cooling the combustion gases being formed within the mass of fuel, and separating the nitrogen compounds from the products of combustion.

7. The herein described process of obtaining nitrogen compounds, which consists in burning under pressure a suitable fuel by means of air, introducing finely divided water in quantities up to 0.8 kg. per 1 kg. of coal and separating the nitrogen compounds from the products of combustion.

8. The herein described process of obtaining nitrogen compounds, which consists in burning under pressure a suitable fuel by means of air, introducing into the fuel finely divided water in quantities up to 0.8 kg. per 1 kg. of coal, adding a nitrogen carrier and separating the nitrogen compounds from the products of combustion.

9. The herein described process of obtaining nitrogen compounds, which consists in burning under pressure a suitable fuel by means of air, introducing into the fuel a suitable amount of finely divided water and a nitrogen carrier, and cooling the combustion gases in the zone of highest temperature and separating the nitrogen compounds from the products of combustion.

In witness whereof I have hereunto set my hand in the presence of two witnesses.

OSCAR BENDER.

Witnesses:

HENRY HASPER,
WOLDEMAR HAUPT.
